UNITED STATES PATENT OFFICE.

DIGBY W. CHANDLER, JR., OF NEW YORK, N. Y., ASSIGNOR TO ANNIN & CO., OF NEW YORK, N. Y., A CORPORATION OF NEW YORK.

DESIGN FOR A CONVENTION BANNER.

Application filed April 15, 1924. Serial No. 9,288. Term of patent 3½ years.

To all whom it may concern:

Be it known that I, DIGBY W. CHANDLER, Jr., a citizen of the United States, and a resident of the city of New York, borough of Manhattan, in the county and State of New York, have invented a new, original, and ornamental Design for a Convention Banner, of which the following is a specification, reference being had to the accompanying drawing, forming part thereof.

The figure is a face view of a convention banner comprising the design.

I claim:

The ornamental design for a convention banner substantially as shown.

DIGBY W. CHANDLER, JR.
